UNITED STATES PATENT OFFICE

WILLIAM A. TEBO, OF ANTHONY, RHODE ISLAND, ASSIGNOR TO DRAPER CORPORATION, OF HOPEDALE, MASSACHUSETTS, A CORPORATION OF MAINE

THIN-PLACE PREVENTER FOR LOOMS

Application filed June 12, 1929. Serial No. 370,336.

This invention relates to improvements in looms and the object thereof is to provide mechanism for preventing thin places in the web of cloth which might be caused by failure of filling either through breakage of filling or exhaustion of filling upon the filling carrier.

It has heretofore been customary to avoid the appearance of thin places in the cloth caused by omission of one or more strands of filling, or by a broken strand of filling, for the operator to rub the cloth from the center toward the selvage or selvages in such a manner as slightly to spread the filling strands, so that the thin place would not be clearly apparent.

One of the objects of the present invention is to provide means for relieving the tension produced by the take-up roll upon the warps in such a manner that the resilience of the warps will draw the fell of the cloth slightly rearwardly upon occurrence of failure of filling, either by breakage or exhaustion of filling upon the filling carrier, so that the next filling which is laid by the shuttle will be beaten up more firmly than it otherwise would and the spaces produced by the failure of filling gradually distributed along the web of cloth, thereby preventing any appearance of a thin place.

A further object of the invention is to provide means operable upon occurrence of failure of filling to move the fell of the cloth positively rearwardly a predetermined distance for the purpose above described.

A further object of the invention is to provide mechanism for accomplishing this purpose which can be conveniently applied to common looms or to automatic filling replenishing looms.

A further object of the invention is to provide mechanism of the character above described which is automatically operable by usual mechanism, such as the filling fork mechanism which operates upon detection of failure of filling to effect a change in the operation of the loom, such as the stoppage of the loom, or the automatic transfer of a filling carrier.

A further object of the invention is to

provide mechanism operable by the beat-up movement of the lay to permit or cause rearward movement of the fell of the cloth which mechanism is brought into operation upon initiation of the change in the operation of the loom.

These and other objects and features of the invention will more fully appear from the following description and the accompanying drawings and will be particularly pointed out in the claims.

In the drawings:

Fig. 1 is a view in side elevation, looking from the center of the loom toward one side, and partially in vertical cross section;

Fig. 2 is a diagrammatic detail elevation showing a whip roll and a guide roll for the cloth in normal operating position;

Fig. 3 is a similar diagrammatic view showing the guide roll and whip roll in the positions assumed when the fell of the cloth has been moved rearwardly; also illustrating in particular the mechanism for actuating these rolls;

Fig. 4 is a front elevation of the sword showing the manner in which the actuating rod is mounted in a slotted plate upon the lay, and illustrating in dotted lines the actuating rod in raised position to effect actuation of the guide roll, or the guide roll and whip roll;

Fig. 5 is a detail view of the usual controller rock shaft with an arm secured thereto for raising the actuating rod into operative position; and

Fig. 6 is a similar view showing the usual controller rock shaft enclosed in a sleeve having an arm for raising the actuating rod into operative position adapted to be employed when the filling fork mechanism calls for a change in the operation of the loom.

A preferred embodiment of the invention is shown as embodied in a usual type of loom which may be either an ordinary loom or a filling replenishing type of loom.

Such a loom is shown as comprising side frames 1, a warp beam 2 journaled therein from which a sheet of warps 3 pass over a whip roll 4 which, as illustrated, is of special construction, thence through the lease

rods 5 and harnesses 6, and over the take-up roll 7, and a small guide roll 8 to the cloth roll 9. The lay 10 is carried by the lay swords 11 which are pivotally carried by the 5 lay rocker shaft 12 at the bottom of the loom. The crank shaft 13 and pitman 14 actuate the lay in the usual manner and the loom is provided with the usual controller rock shaft 15 which, upon initiation of filling 10 replenishment, is rocked in a counter-clockwise direction.

The mechanism herein described, except for the special form of the whip roll, may be and preferably is of the usual type.

15 The present invention contemplates the provision of means located rearwardly of the take-up roll adapted to be operated in such a manner as to release the tension upon the warps upon occurrence of failure of filling, either by breakage or exhaustion, to permit or cause the fell of the cloth to be drawn rearwardly a very short distance, so that when the filling is beaten up, upon continuation of the operation of the loom, no 20 space will be left because of the missing pick or picks of filling which otherwise would occur if a broken end of filling were drawn out by the weaver, or if a delay of one or more picks occurred during filling replenishment.

25 A preferred means of accomplishing this purpose comprises means, located rearwardly of the take-up roll, movable transversely of the web of cloth, operable upon occurrence of failure of filling to slacken the tension imposed upon the warp, thereby permitting the resilience of the warps to draw the fell of the cloth rearwardly a short distance. Preferably, however, means are provided in addition thereto for positively moving 30 the fell of the cloth rearwardly a predetermined distance.

35 As illustrated in the accompanying drawings a guide roll 16 for the web of cloth, suitably journaled in the side frames, is located rearwardly of, and preferably in proximity to, the take-up roll 7, and acts to support the web of cloth as it approaches the take-up roll. The main body portion of this roll is cylindrical, but is formed with an eccentric 40 segmental section 17 producing a radial enlargement which extends longitudinally of the roll throughout its length and normally supports the web of cloth above the position which would be assumed by it if it engaged 45 the cylindrical surface 18 of the roll.

50 Means are provided for rotating this guide roll preferably in a clockwise direction upon occurrence of failure of filling in such a manner as to move the eccentric segmental section 55 from beneath the cloth and permit the cloth to engage the cylindrical portion of the roll, thereby reducing the tension imposed upon the cloth by the take-up roll, so that the resilience of the warps may draw 60 the fell of the cloth slightly rearwardly.

65 By virtue of this movement of the fell of the cloth the next filling which is beaten up after a broken end is removed, or after the pick of a shuttle containing an exhausted filling carrier, will be properly laid in the 70 fell of the cloth. The frictional engagement of the surface of the guide roll 16 by the cloth will, upon continuation of the weaving operation, gradually rotate the guide roll in a counter-clockwise direction, thereby bringing 75 the eccentric surface of the guide roll in a position to support the web of the cloth in the manner above described.

80 Any suitable means may be provided for actuating the guide roll and for limiting its movement. As illustrated in the drawings the guide roll 16 has secured to it an arm 19 which, when the guide roll is in normal position with the eccentric segment thereof supporting the warp, engages a suitable stop, 85 such as a pin 20 projecting from the loom side.

85 Any suitable means, either manual or automatic, may be employed for rotating the guide roll 16 in a counter-clockwise direction 90 to relieve the tension upon the warps. As illustrated herein an actuating rod 21 is pivotally connected to the free end of the arm 20 and extends downwardly and horizontally through a slot 22 in a guide plate 23 which 95 is attached to the sword 11. The lower portion of the bar 21 desirably is curved upon an arc substantially concentric with the axis of the lay rock shaft and is supported near its end by a pin 24 projecting from the loom side.

100 A hooked plate 25 is adjustably secured in a recess 26 of the actuating bar 21 by a screw and slot connection 27 and 28. The slot 22 in the plate 23 is of such length that when the bar 21 is in lowered position and supported upon the pin 24, the hooked plate will pass freely through the slot 22, as illustrated in full lines in Fig. 4, but when the bar 21 is raised to the dotted line position in Fig. 4, 110 the hooked plate 25 will engage the upper wall 29 of the slot 22, so that upon beat-up of the lay the rod 21 will be moved end-wise, thereby swinging the arm 19 of the take-up roll to the left, as illustrated in Fig. 3, and 115 causing a rotation of the guide roll 16 in a clockwise direction.

120 Desirably the means for raising the rod 21 is actuated by means for initiating a change in the action of the loom upon detection of failure of filling. As illustrated in Fig. 1 an arm 30 is rigidly secured to the controller rock shaft 15 and extends upwardly and laterally over the breast beam and is connected, preferably by a spiral spring 31, to the arm 21. 125

130 In the operation of the loom the counter-clockwise rotation of the controller rock shaft upon detection of failure of filling rotates the arm 30 in a counter-clockwise direction, thereby acting through the spring 31 to raise

the hooked plate 25 sufficiently to cause the hooked end thereof to engage the upper wall 29 of the slot as aforesaid, thus causing the guide roll to be rotated in a clockwise direction opposite to the direction of movement of the warps during the weaving operation to slacken the tension imposed by the take-up roll upon the warp without modifying the action of the take-up roll, or of the warp beam.

While the resilience of the warp may be sufficient in many instances to accomplish the purposes above described, desirably means are provided for positively moving the fell 15 of the cloth rearwardly a short distance. This is accomplished in the present embodiment of the invention by providing the whip roll 4 with a radial enlargement or eccentric segmental section 32 similar to that of the 20 guide roll 16, and by providing the whip roll 32 with an arm 33 which is suitably connected to the arm 19 of the guide roll as by a link or bar 34. During the normal weaving operation the warps 3 pass from the warp 25 beam over the cylindrical portion 35 of the whip roll, the segmental section 32 being beneath the plane of the warps leading from the cylindrical section to the eccentric segment 17 of the guide roll 16. When, therefore, 30 the guide roll 16 is rotated in a clockwise direction, which is opposite to the direction of movement of the warps during the weaving operation, by engagement of the plate 23 upon the sword with the hooked plate 27, the whip roll 4 will be rotated similarly in a clockwise direction causing the eccentric segmental section or radial enlargement 32 thereof to engage the warps, as illustrated in Fig. 3, and draw them rearwardly, 35 in a direction opposite to the direction of their movement during the weaving operation, a predetermined distance, thus taking up the slack in the cloth which is produced by the rotation of the eccentric segment 17 of the 40 whip roll out of engagement with the cloth, so that the fell of cloth will be positively drawn rearwardly a desired predetermined distance.

Inasmuch as the controller rock shaft is 45 but momentarily operated to initiate a change in the operation of the loom, the actuating rod 21 will immediately drop to its lowered position after the counterclockwise rotation of the guide roll and whip roll have been accomplished. Upon continuation of the 50 weaving operation the engagement of the web of cloth with the surface of the whip roll and with the surface of the guide roll 17 will gradually rotate these rolls in a counterclockwise direction and restore them to their 55 position of normal operation, illustrated in Fig. 2, and consequently gradually permit the fell of cloth to assume its normal position after the temporary rearward movement thereof has accomplished its purpose.

Where the invention is applied to a feeler loom in which the controller rock shaft 15 is actuated to initiate transfer, upon detection of substantial exhaustion of filling by the feeler, the arm 30, which raises the actuating rod 21, may be, and desirably is, secured to a sleeve shaft 36 which is rotatably mounted upon the controller rock shaft 15, and is actuated by the filling fork mechanism upon detection of failure of filling in the manner 75 above described.

This invention, therefore, is applicable either to looms in which a change in the operation of the loom, such as stoppage of the loom or filling replenishment, is initiated upon 80 failure of filling by the action of the filling fork, or to feeler looms in which transfer is initiated by the feeler mechanism.

It will be obvious that the mechanism for relieving the tension upon the looms may 85 be alone operated to permit a rearward movement of the fell by merely omitting the connecting bar or link 34, in which case a usual cylindrical whip roll may be employed, or if a special whip roll having an eccentric seg- 90 ment is employed it may be rendered inoperative by disconnecting or removing the connecting link or rod 34 and providing suitable means to prevent clockwise rotation of the 95 arm 33.

It will thus be seen that the fell of the cloth may be caused to move slightly rearwardly by the resilience of the warps upon the slackening of the tension upon the cloth produced by the take-up roll, or the fell of 100 the cloth may be positively moved rearwardly a predetermined distance by the conjoint action of the guide roll and the whip roll as above described.

Having thus described the invention, what 105 is claimed as new, and desired to be secured by Letters Patent, is:

1. A loom comprising a warp beam, a take-up roll, and means operable upon detection of failure of filling to effect a change in the 110 operation of the loom, means movable by frictional engagement of the web of cloth during the normal operation of the loom to increase the tension upon the warps, means operable by the means for effecting the change in 115 the operation of the loom to slacken the tension thus imposed upon the warps, thereby permitting a limited rearward movement of the fell of the cloth and preventing the formation of a thin place upon continuation of 120 the weaving operation.

2. A loom comprising a warp beam and a take-up roll, and means operable by a filling fork upon detection of failure of filling to effect a change in the operation of the loom, 125 means movable transversely of the plane of the web of cloth by frictional engagement with the web of cloth during the forward movement thereof to increase the tension upon the warps, means operable upon initia- 130

tion of a change in the operation of the loom to cause said tension increasing means to slacken the tension imposed upon the warps, thereby permitting a limited rearward movement of the fell of the cloth and preventing the formation of a thin place upon continuation of the weaving operation.

3. A loom comprising a warp beam and a take-up roll, a rotatable roll having an eccentric segmental section extending longitudinally thereof, located rearwardly of said take-up roll, engaging the web of cloth, and rotatable by the movement thereof sufficiently to cause said eccentric segment normally to support the web of cloth, means for rotating said roll in the opposite direction upon failure of filling temporarily to slacken the tension imposed upon the warps by the take-up roll and to permit a limited rearward movement of the fell of the cloth thereby preventing the formation of a thin place upon continuation of the weaving operation.

4. A loom comprising a warp beam and a take-up roll, a rotatable roll having an eccentric segmental section extending longitudinally thereof, located rearwardly of said take-up roll, engaging the web of cloth, and rotatable by the movement thereof sufficiently to cause said eccentric segment normally to support the web of cloth, means operable by a filling fork, upon detection of failure of filling, to effect a change in the operation of the loom, and means operable upon initiation of such change to rotate said roll in the opposite direction temporarily to slacken the tension imposed upon the warps by the take-up roll and thereby prevent formation of a thin place upon continuation of the weaving operation.

40 5. A loom comprising a warp beam and a take-up roll, a rotatable roll having an eccentric segmental section extending longitudinally thereof, located rearwardly of said take-up roll, engaging the web of cloth, and rotatable by the movement thereof sufficiently to cause said eccentric segment normally to support the web of cloth, a rod pivotally connected to said roll eccentrically thereof, a support for the free end of the rod, a rocking lay, co-operating means on said rod and the lay normally disengaged, means operable by a filling fork to effect a change in the operation of the loom, and means actuated upon initiation of such change in the operation of the loom to effect engagement between said co-operating means and thereby cause the lay to shift the rod and rotate said roll in a direction to relieve the tension upon the warp and permit the fell of the cloth to move rearwardly, thereby preventing the formation of a thin place in the cloth upon continuation of the weaving operation.

60 6. A loom comprising a warp beam and a take-up roll, a rotatable roll having an eccentric segmental section extending longitudinally thereof located rearwardly of

dinarily thereof, located rearwardly of said take-up roll, engaging the web of cloth, and rotatable by the movement thereof sufficiently to cause said eccentric segment normally to support the web of cloth, a rod pivotally connected to said roll eccentrically thereof, a support for the free end of the rod, a rocking lay, co-operating means on said rod and the lay normally disengaged, a rotatable member operable by a filling fork to initiate a change in the operation of the loom, an arm rigid with said rotatable member yieldably connected to said rod and operable upon initiation of said change in the operation of the loom to effect engagement of the co-operating means upon said rod and said lay to cause the lay to shift the rod and rotate the roll in a direction to relieve the tension upon the warps and permit the fell of the cloth to move rearwardly, thereby preventing the formation of a thin place in the cloth upon continuation of the weaving operation.

70 7. A loom comprising a warp beam and a take-up roll, means operable by a filling fork upon detection of failure of filling to initiate a change in the operation of the loom, rotatable means located respectively in proximity to said warp beam and take-up roll frictionally engaging and supporting the warp and web of cloth, and operable by forward movement of the cloth to increase the tension upon the warps, and means operable upon initiation of said change in the operation of the loom to rotate said supporting means in a reverse direction to move the fell of the cloth positively rearwardly and thereafter to permit gradual restoration of said increased tension by the movement of the cloth upon continuation of the weaving operation.

75 8. A loom comprising a warp beam and a take-up roll, a rotatable guide roll having an eccentric segmental section extending longitudinally thereof located rearwardly of and in proximity to said take-up roll, a whip roll having an eccentric segmental section extending longitudinally thereof, said rolls engaging respectively the web of cloth and the warp sheet and rotatable by the movement thereof during the weaving operation sufficient to cause the eccentric segment of said guide roll normally to support the web of cloth and the segmental section of the whip roll to lie beneath the plane of the warp sheet, and means operable upon occurrence of failure of filling to rotate said guide roll and said whip roll in a direction opposite to the direction of movement of the warps, thereby positively moving the fell of the cloth rearwardly a predetermined distance to prevent formation of a thin place in the cloth upon continuation of the weaving operation.

80 9. A loom comprising a warp beam and a take-up roll, a rotatable guide roll having an eccentric segmental section extending longitudinally thereof located rearwardly of

and in proximity to said take-up roll, a whip roll having an eccentric segmental section extending longitudinally thereof, said rolls engaging respectively the web of cloth and the warp sheet and rotatable by the movement thereof during the weaving operation sufficient to cause the eccentric segment of said guide roll normally to support the web of cloth and the segmental section of the whip roll to lie beneath the plane of the warp sheet, arms rigidly connected to and extending from the respective rolls, a rod connecting said arms, and means operable upon occurrence of failure of filling to rotate said rolls simultaneously in a direction opposite to the direction of movement of the warps during the weaving operation temporarily to move the fell of the cloth rearwardly, thereby preventing the formation of a thin place in the cloth upon continuation of the weaving operation.

10. A loom comprising a warp beam and a take-up roll, a rotatable guide roll having an eccentric segmental section extending longitudinally thereof located rearwardly of and in proximity to said take-up roll, a whip roll having an eccentric segmental section extending longitudinally thereof, said rolls engaging respectively the web of cloth and the warp sheet and rotatable by the movement thereof during the weaving operation sufficient to cause the eccentric segment of said guide roll normally to support the web of cloth and the segmental section of the whip roll to lie beneath the plane of the warp sheet, arms rigidly connected to and extending from the respective rolls, a rod connecting said arms, operable to rotate said rolls in unison, means including a controller rock shaft operable by a filling fork to effect a change in the operation of the loom, means connected to the arm of one of said rolls and to said controller rock shaft operable upon initiation of the change in the operation of the loom to cause said rolls to rotate in a direction opposite to the direction of movement of the warps during the filling operation and thereby temporarily to move the fell of the cloth rearwardly, thereby preventing the formation of a thin place in the cloth upon continuation of the weaving operation.

In testimony whereof, I have signed my name to this specification.

WILLIAM A. TEBO.
